(57) **CLAIM**

The ornamental design for an automobile battery connector, as shown and described.

DESCRIPTION

FIG. 1 is a front, top and right-side perspective view of an automobile battery connector showing my new design; FIG. 2 is a front, top and left-side perspective view thereof; FIG. 3 is a front view thereof, the rear view being a mirror image of FIG. 3;

FIG. 4 is a top plan view thereof;

FIG. 5 is a bottom plan view thereof;

FIG. 6 is a right side view thereof; and,

FIG. 7 is a left side view thereof.
